HEAD REST

Kenneth C. Kerr, 1222 S. Riverside, Medford, Oreg.

Filed Feb. 12, 1962, Ser. No. 68,759

Term of patent 14 years

(Cl. D15—3)

FIG. 1

FIG. 2

FIG. 3

I claim:

The ornamental design for a head rest, as shown.
